[57] CLAIM

The ornamental design for a anti-theft tag for store merchandising, as shown and described.

DESCRIPTION

FIG. 1 is a perspective view of an anti-theft tag for store merchandising showing my new design;

FIG. 2 is a side elevational view of the tag housing element thereof;

FIG. 3 is a side elevational view of the tag pin element thereof;

FIG. 4 is a perspective view of the tag pin element thereof; and,

FIG. 5 is a perspective view of the tag housing element thereof.

The tag and both elements are symmetrical about a vertical axis.
